UNITED STATES PATENT OFFICE.

EMILY E. GSTALDER, OF TOLEDO, OHIO.

ADJUSTABLE HATBAND.

Application filed October 2, 1926. Serial No. 189,137.

The present invention relates to head dress apparel, and more specifically to improvements in bands for hats of various types.

The primary object of the invention resides in the provision of an adjustable hat band primarily intended for use within hats of various types for causing the hat to fit more comfortably upon one's head when the hat is being worn, and which band also serves to make the hat cling more snugly to one's head.

A further object of the invention resides in the provision of an adjustable hat band intended to be substituted for the usual sweat band of the hat for permitting of the inner perimeter of the crown of the hat to be reduced to a size suitable to the size of the head of the wearer of the hat.

A still further object of the invention resides in the provision of an improved type of adjustable hat band having means for contracting of the band at different portions thereof, and which band is of such construction as to permit of its being readily contracted without causing a gathering of the material of which the band is formed.

A still further object of the invention is to provide an adjustable hat band embodying a pair of fabric band sections so cut and joined together in annular formation as to permit of but relatively little stretching of the annulus at its point of attachment to the head size of the hat, and allowing a greater amount of stretching at the opposite or upper edge of the annulus.

A still further object of the invention is to provide an improved type of adjustable hat band which may be economically manufactured, one which will be durable and efficient in use, and which band is susceptible of use either in connection with ladies' or men's hats of various types.

Other objects and advantages of the invention will be apparent during the course of the following detailed description, taken in connection with the accompanying drawing forming a part of this specification and in which drawing:

Figure 1 is a vertical section through a hat and showing the improved band in position within the crown of the hat, the band being shown in perspective and having a portion broken away for illustrating certain details of construction.

Figure 2 is a vertical section through the hat and band.

Figure 3 is a fragmentary sectional view through the hat and showing the band in elevation and showing the band contracted for reducing the head size of the hat.

Figure 4 is an enlarged fragmentary vertical sectional view illustrating the specific construction of the band and showing one manner of attachment of the band to the hat.

Referring to the drawing in detail, and wherein similar reference characters designate corresponding parts throughout the several views, the letter A may designate a hat of any preferred type, and B the improved hat band for reducing of the head size of the hat. The hat A may be of any preferred type, and comprises a crown 5 provided with a straight side wall 6, and a brim 7.

The band B comprises an annular body preferably formed of a comparatively flexible fabric, and embodies major and minor band sections 8 and 9 respectively.

The major band section 8 is preferably formed of loosely woven fabric of a comparatively flexible nature and which fabric is cut on the bias of the material. The material from which the major band section 8 is formed, is preferably of a nature capable of retaining the band in annular formation and against possible collapsing of the wall 85 of the body.

The minor band section 9, and which is also cut on the bias of the material, is preferably formed of a fabric having a close texture, and this minor band section may be 90 termed a lining, since the same is disposed inwardly of the major band section 8. The major band section 8 may also be termed a net portion, since the same is preferably formed of a loosely woven material.

The lower edges of the sections 8 and 9 are doubled outwardly upon the lower portion of the band as at 10, with the doubled back portion of the major band section 8 preferably extending upwardly past the 100 turned up portion of the minor band section 9 as clearly illustrated in Figure 4. These upwardly and outwardly turned lower edges of the sections 8 and 9, are secured to the lower portion of the band as by means of a 105 line of through and through stitching 11 disposed relatively close to the lower edge of the band and passing through the upper

end of the upwardly turned portion of minor band section 9. Spaced closely above the annular row of stitching 11, is an annular row of stitching 12 which extends 5 through the sections 8 and 9 and the upper end of the upwardly turned portion of the major band section 8. Thus it will be seen that the lower portion of the band B is stiffened to a certain extent by means of the 10 closely arranged annular rows of stitchings 11 and 12.

Spaced closely above the annular row of stitching 12, is an annular row of stitching 13 which extends through the sections 8 and 15 9 and forms an annular casing 14 between the sections 8 and 9.

The upper edge of the lining or minor band section 9 is doubled outwardly and downwardly as at 15 above the top edge of 20 the net or major band section 8 and secured by means of an annular row of stitching 16 for forming an annular pocket 17 at the upper or top edge of the band B.

The sections 8 and 9 are joined together 25 in any suitable manner as at 18 for forming the annular body.

Extending through the annular casing 14, and having its ends projecting from the casing at the joint 18, is a draw string 19 preferably of an elastic nature, and which draw-string acts for contracting of the hat band at a point near the lower edge of the band and lower than one-half of the height of the band. The projecting end of the string 19 35 may be knotted as at 20 for adjustably retaining the lower portion of the band in its adjusted contracted condition.

Extending through the annular pocket 17 formed at the upper end of the band, is a 40 second draw string 21 preferably of an elastic nature, and this draw string acts for contracting of the hat band at its upper edge independently of the action of the lower draw string 19. The free end of the draw string 21 preferably projects from the 45 pocket at the joint 18 and may be knotted as at 22 for adjustably retaining the upper edge of the band in its adjusted contracted condition. The lower doubled edge of the 50 band may be secured to the lower portion of the wall 6 of the hat crown in any desired manner, and in the example shown the band has been attached by means of suitable 55 stitchings 23. When the band is secured inwardly of the crown 5, and in its normal position, the same preferably extends in close proximity to the inner surface of the wall 6 as is illustrated in Figure 2.

After the band has been secured inwardly 60 of the crown of the hat, the elastic draw string 19 may first be tightened for contracting of the lower portion of the band to the proper head size for causing the 65 hat to fit comfortably upon the head of the wearer. The upper draw string 21

may then be tightened for either contracting the upper portion of the band an equal amount as that of the lower portion of the band, or to a greater degree as illustrated 70 in Figure 3 should such become desirable for causing the hat to fit properly and cling to the wearer's head. Thus it will be seen that the draw strings 19 and 21 will permit of the annular body to be contracted to different degrees at its lower and 75 upper portions in accordance with the desires of the wearer. It will be seen that by so arranging the draw strings 19 and 21, that the band is caused to cling to the head throughout the entire inner surface of 80 the band and thus materially aid in resisting movement of the hat off the head aside from causing the hat to feel comfortable.

As before stated, both of the sections 8 and 9 are cut on the bias of the material 85 from which they are formed, and by so closely arranging the annular rows of stitchings 11, 12 and 13 at the lower portion of the band, will prevent any great amount of stretching of the band below the draw 90 string 19, and which stretching of the lower edge of the band would be undesirable. It will readily be apparent, owing to the bias cut of the material, that slight expansion and contraction of the lower portion of the 95 band is possible upon loosening and tightening of the draw string 19. It will also be seen that but one annular row of stitching is provided at the upper edge of the band, and which single row of stitching will permit of the upper edge of the band to be contracted and expanded considerably more than the lower portion of the band. When the draw strings 19 and 21 are tightened for contracting of the band, the material 100 will not pucker or fold into ridges which would be undesirable, owing to the fact that both of the sections 8 and 9 are cut on the bias of the material from which they are formed.

It may here be well to again state that the device is intended to be substituted for the usual sweat band as provided in certain types of hats, and therefore the band is formed relatively narrow since the band is 115 merely intended to engage the side portions of one's head.

From the foregoing description it will be apparent that a novel and efficient type of 120 adjustable hat band has been provided whereby the same may be properly adjusted for causing the hat to which the same is applied to fit more comfortably upon one's head when the hat is being worn, and which band may be contracted at different portions without liability of the material pucking and forming undesirable corrugations at the gathered portion of the band.

Changes in detail may be made to the 125 specific form of the invention herein shown 130

and described, without departing from the spirit of the invention or the scope of the following claims.

I claim:

5. 1. A hat band comprising a narrow annular body formed of flexible material and adapted to be secured at its lower edge to the inner side of a hat crown, said body having a plurality of annular rows of stitching provided adjacent its lower edge and a single annular row of stitching disposed adjacent the upper or free edge of the body, and annularly extending elastic draw strings carried by the upper and lower 10 edges of the annular body for independent contracting of the upper and lower edges of the body.
2. A hat band comprising a narrow annular body formed of flexible material and 20 adapted to be secured at its lower margin to the inner side of a hat crown, annular rows of stitchings provided at the lower edge of the body and spaced relatively close together with two adjacent rows of stitchings 25 providing an annular casing, an elastic draw string arranged in the annular casing for contracting of the lower portion of the annular body, an annular row of stitching provided at the upper edge of the body and 30 forming an annular pocket at the upper edge of the body, and a second elastic draw string extending in the pocket for contracting of the upper portion of the annular body independently of the lower portion of 35 the body.
3. A hat band comprising a narrow annular body formed of fabric cut on the bias of the material, closely arranged annular rows of stitching provided at the lower edge 40 of the annular body with the two uppermost rows of stitchings providing an annular casing, an elastic draw string extending through the casing for contracting of the upper portion of the annular body.

lower portion of the body, a single row of 45 stitching provided at the upper edge of the annular body and forming an annular pocket, and a second elastic draw string extending through the pocket for contracting of the upper edge of the annular body.

5. A hat band comprising a narrow annular body embodying major and minor band sections, said major band section being formed of a heavy texture, annular rows of 50 stitchings connecting the lower portions of the band sections and arranged relatively close to the lower edge of the annular body, an elastic draw string carried by and disposed adjacent the annular rows of stitching 55 for contracting of the lower portion of the annular body, a single row of stitching connecting the upper portion of the band sections and providing an annular pocket at the upper edge of the body, and a second elastic band extending through the pocket 60 for contracting of the upper portion of the body.

6. A hat band comprising a narrow annular body embodying major and minor 65 fabric band sections cut on the bias of the material; closely spaced annular rows of 70 stitchings connecting the lower portions of the fabric band sections and arranged closely adjacent the lower edge of the annular body with the two uppermost rows of 75 stitchings forming an annular casing, an annular draw string extending through the casing for contracting of the annular body directly above the annular rows of stitching, a single row of stitching connecting the fabric band sections at their upper 80 edges and providing an annular pocket at the top edge of the body, and a second elastic draw string arranged in the annular 85 pocket for contracting of the upper portion of the annular body.
